UNITED STATES PATENT OFFICE.

DANIEL C. POWERS, OF CLEVELAND, OHIO.

STOP AND WASTE COCK.

No. 829,124

Specification of Letters Patent.

Patented Aug. 21, 1906.

Application filed June 9, 1904. Serial No. 211,811.

To all whom it may concern:

Be it known that I, DANIEL C. POWERS, a citizen of the United States, residing at Cleveland, in the county of Cuyahoga and 5 State of Ohio, have invented certain new and useful Improvements in Stop and Waste Cocks; and I do hereby declare the following to be a full, clear, and exact description of the invention, such as will enable others 10 skilled in the art to which it pertains to make and use the same.

My invention relates to interchangeable right and left stop and waste cocks, and has for its object, first, convenience in interchanging the parts; second, the retaining of the 15 stop in position; third, the protection of the stop devices from dirt and the convenience in assembling the parts.

With the above objects in view my invention 20 consists in the parts and combination of parts hereinafter fully set forth and claimed.

In the drawings, Figure I is a view in elevation, illustrating a stop and waste cock constructed according to my invention, showing 25 the parts constituting the same separated and in relative position. Fig. II is a cross-sectional view taken on line 2 2, Fig. I. Fig. III is a vertical section taken through line 3 3, Fig. I. Fig. IV is a top plan view of 30 the cock.

A represents the body or shell of the cock, having the usual connections a a' and the waste hole or orifice a^2 . At the upper portion of the body A is provided the flange A', 35 with its cut-away portion forming stops s s' . B represents the plug fit and ground into its seat within the body or shell A in the usual manner. This plug B has the ordinary or usual waterway B' and the wastewater leading 40 from one side thereof, as is usual.

The plug B is formed with a polygonal socket B² for the reception of a key or handle C, and leading into this socket B² is a screw-threaded orifice b, adapted to receive a screw. 45 The plug B is also provided with holes or orifices O O', which are preferably drilled part way through the plug, as illustrated in Fig. II of the drawings, and are disposed at right angles to each other. The orifices O O' are 50 drilled or formed to loosely receive a pin P, which forms a stop for the plug. This pin P

projects out from the plug when properly seated, so that its end will engage the stop s' and allow the rotation of the plug B to the extent of the distance between the stops s s'. 55 The changing of the pin P from the hole O to the hole O' in the plug determines the direction of the flow of the waste from right to left, or vice versa, and it is with this part of the device that this invention especially 60 pertains. The looseness of the pin P in the orifice O or O' allows it to be readily placed in either orifice, according to requirements, and to be readily abstracted therefrom without the use of tools; but in order to retain it 65 when it has been properly located I provide the cap C, which fits over the upper end of the plug B and down around the upper end of the body or casing of the plug A, as illustrated in Fig. III of the drawings. This casting or cap C' performs two functions. First, it acts to retain the pin P in its proper relation to the plug as a stop in either of the holes O or O' and at the same time forms a dirt 70 guard or shield for the stop mechanism. 75 The manner of securing this cap C' in position is by means of the screw S, which passes through an orifice c in the cap C' and from thence into the screw-threaded orifice b, where in case a handle is used, as illustrated 80 in Fig. I, a screw S will impinge upon the same and hold it in place.

In setting forth this invention I have shown and described mechanical details and assemblage of parts as I consider them best 85 adapted to perform their functions; but I do not wish, therefore, to be limited in this invention, as they may be departed from in modifying the construction.

What I claim is—

In a stop-cock, a body or casing; a plug seated in the casing and provided in its larger end with two holes arranged at or approximately at a right angle to each other and extending inwardly a suitable distance from the 95 peripheral surface of the plug; a pin loosely engaging one of the said holes and projecting a suitable distance outwardly beyond the peripheral surface of the plug; a suitably-supported cap surrounding the larger end of the plug and having a portion arranged to overlap the outer end of the pin in either posi- 100

tion of the plug, and two stops formed on the casing and spaced circumferentially of the pin-bearing portion of the plug, with the arrangement of the parts such that one or the other stop is engaged by or adjacent the pin according as the plug is in the one or the other of its positions.

Signed at Cleveland, in the county of Cuyahoga and State of Ohio, this 2d day of May, 1904.

DANIEL C. POWERS.
